Primary Examiner—Philip S. Hyder

[57] CLAIM

The ornamental design for a "sports utility bag", as shown and described.

DESCRIPTION

FIG. 1 is a perspective view of a sports utility bag showing our new design;

FIG. 2 is a front view thereof;

FIG. 3 is a top plan view thereof; and,

FIG. 4 is a bottom view thereof.

The broken line portions of the drawings are for illustrative purposes only and forms no part of the claimed design.
